UNITED STATES PATENT OFFICE

FRED UTTLEY, OF CORONA, NEW YORK

DOBBY-LOOM CHAIN PEGGING MACHINE

Application filed March 7, 1929. Serial No. 344,989.

This invention relates to pegging machines and is directed more particularly to improvements in pegging machines of the character described and claimed in my Patent No. 1,520,159, issued December 23, 1924. In the patented machine, mechanism is provided for the pegging of loom bars in a thoroughly efficient and practical manner. The bars, which in practice take the form of perforated 10 wooden bars are supported and successively fed into a position wherein pegs may be mechanically delivered to and secured in predetermined perforations of the bars. The pegs are normally contained in the hopper 15 or magazine and are adapted to be fed by a key board operated escapement and in a selective manner into positions with reference to predetermined holes in the bars, and after a series of pegs have been positioned for association with any particular bar, manually 20 operable means is utilized to screw all of such pegs simultaneously into the corresponding holes in the bar.

The present invention operates upon the 25 same general underlying principle, but differs from my prior achievement, among other features, in the provision of improved means and mechanism of feeding the pegs into position to be applied to the bars, in improved 30 and novel means for applying such pegs to the bar, and in improved and novel means in the selective feed of the pegs into positions to be applied.

A further important feature of the invention 35 consists in the provision of means to facilitate or guide the operations of the keyboard in order that an operator may more readily determine the particular keys which are to be actuated in order to effect a predetermined positioning of the pegs with respect 40 to the respective bars.

Another highly important feature of the 45 present invention consists in the provision of mechanism, so constituted that a loom chain may be fed to the machine with pegs associated therewith, a mechanism functioning to remove the pegs which are associated with the bars and to thereafter apply other pegs in predetermined positions appropriate 50 to the new design to be produced through the

employment of such chain. Through the utilization of the foregoing features, and others, the efficiency of the machine of my prior patent is materially increased and it is made possible to utilize such machine in a 55 more universal manner than heretofore possible.

A further important improvement is found in the ability of the machine to operate with 60 chains of all sizes.

Features of the invention, other than those specified, will be apparent from the herein-after detailed description and claims, when read in conjunction with the accompanying 65 drawings.

The accompanying drawings illustrate one practical embodiment of the invention, but the construction therein shown is to be understood as illustrative, only, and not as defining the limits of the invention.

Figure 1 is a side elevation of a machine embodying the present invention.

Figure 2 is a fragmental elevation of the machine showing the operating parts thereof in a different position than exhibited in 75 Figure 1.

Figure 3 is a fragmental section illustrating certain parts in elevation which are shown in dotted lines in Figure 1.

Figure 4 is a vertical section through the 80 machine showing the parts in certain operative positions.

Figures 5 and 6 are fragmentary sections corresponding to the section of Figure 4, but showing the operating parts in different positions.

Figure 7 is a section perspective of one of the parts shown in section in Figures 4 to 6 inclusive.

Figure 8 is a face view of the circumference of the upper roll of the machine.

Figure 9 is a like view of the lower roll of the machine showing the mounting for said roll in horizontal section.

Figure 10 shows a filler piece or spacing 95 block adapted for association with either the upper or lower roll.

Figure 11 is a vertical section of mechanism for assisting the operator in determining the operation of the keyboard.

Figure 12 is a section on the line 12—12 of Fig. 11.

Figure 13 shows the operating mechanism for the apparatus of Fig. 11.

5 Figure 14 is a perspective view of one of the tracks or troughs leading from the magazine and associated therewith and escapement mechanism for permitting the feed of the pegs selectively therethrough.

10 Figure 15 is a side elevation of the trough of Fig. 14 with the escapement or feed plates removed in the interest of clearness.

Figure 16 is a section on the line 16—16 of Figure 15 with the plates in position.

15 Figure 17 is a fragmental perspective of certain mechanism illustrated in section in Figure 4.

Figure 18 is a perspective view of one of the parts shown in section in Figure 4.

20 Referring to the drawings, 1 designates the base of the machine. On the rear portion of this base are upstanding side plates 2 and 3 rigidly secured to the base in upstanding parallel relation to one another. Between these side plates are mounted two carrier rolls 4 and 5 placed one above the other and both mounted to rotate. The upper roll 5 is mounted to rotate in any suitable fixed bearings carried by the side plates, while the 25 lower roll 4 is mounted in bearings of the character shown in Fig. 9. As here illustrated, the roll is provided at its opposite ends with trunnions 6 which pass thru bearing blocks 7 and are journaled for rotation 30 therein. These bearing blocks are mounted to slide in 45 degree angle slots in the side bars 2 and 3.

35 Mounted on the exterior face of the plate 3 is a ring or annulus 8 at diametrically opposite sides of which are formed helical slots 11, the axis of which slots is the axis of the roll 4. Extending through the slots is an operating lever 9 and this lever is perforated as shown to fit over the trunnion 6. A large headed screw 10 is screwed into the end of the trunnion and binds the operating lever to the trunnion while permitting the trunnion to rotate.

40 By a relatively small amount of arcuate movement of the operating lever, the bearing blocks 7 at both ends of the roll are slid longitudinally to shift the same laterally in one direction or the other to a predetermined degree as hereinafter more fully explained.

45 Suffice it here to say that the purpose of this mounting is to permit the machine to operate with bars embodying either a double row of peg holes or a single set of peg holes appropriate respectively to the so-called "double harness" or "single harness" operation.

50 The sliding bar block arrangement shown in Fig. 9 is duplicated at both ends of the roll 4, although the ring 8 and operating lever 9 are used at only one end of the roll.

The trunnion at the other end of the roll is extended and has mounted thereon exteriorly of the side plate 2 a ratchet wheel or gear 12, which, when rotated, with step by step movement, imparts a like movement 70 to the roll 4.

Both the rolls 4 and 5 are provided in their outer circumference with depressions or recesses forming pockets 14 and 15 adapted for the reception of loom chain bars which are designated generally by the reference character C in the respective figures. The pockets 14 and 15 are spaced equidistant around the circumference of the respective rolls and at such distance apart that when the bars are linked together to form the chain as is common in practice, this chain of bars is adapted to pass about the respective rolls as indicated in Figs. 4, 5 and 6, the respective bars engaging the recesses of pockets 15 and 14 as indicated in these figures.

75 It may be here noted that the roll 4 is the pegging roll, i. e., the roll at which the pegs are applied, whereas the roll 5 is the roll adjacent which the previously used pegs are 80 removed from the bars.

85 In the machine of my prior patent, no means was provided for removing the pegs after the card chain had been used. They have heretofore been removed by hand. The present machine is so constructed that a used chain may be run through the machine, the machine functioning first to remove the pegs already in the chain and to thereupon feed the chain by a step by step movement to a 90 point of application of pegs for the new arrangement or set up desired. To this end the chain is fed first over the roll 5 and directly upon leaving said roll comes into cooperative 95 relation with peg removing means indicated generally by the reference character 16; here all the pegs are removed from the bars as each bar is in cooperative relation to said means. The bars pass from said means free of pegs 100 and to the roll 4. While the bars are retained in the pockets of the roll 4, the new peg arrangement is applied. My prior patent shows key board operated mechanism for applying pegs to bars and the same general arrangement is employed in the present machine 105 with, however, such improvements as practice has shown to be desirable.

110 Thus in the accompanying drawings, 17 designates a magazine in which the pegs are adapted to be contained and they are adapted to be fed from this magazine or hopper by means of a number of tracks or guides 18 to a series of wrenches 19, in substantially the same manner as described in connection with my prior patent. The feed of the pegs to the 115 wrenches selectively is controlled by a key board operated escapement or feeding device. The keys are designated 20 and are actuated the same as typewriter keys by the fingers of the operator. Each of these keys controls 120

the escapement or feed mechanism of one of the tracks 18. Thus, as shown in Fig. 4, for example, the rear end of the key lever 21 engages with the hook end 22 of the swinging plate 23, which is provided at its upper end with a nose 24.

The normal position of the parts is as illustrated in Figure 4, wherein it will be noted that the nose 24 of the plate is in retracted position between the ends and in cooperative relation with escapement mechanism. This mechanism which is shown in detail in Figures 14, 15 and 16 embodies a pivoted member 25 mounted on a pivot pin 26 with which co-operates a spring 27. To the member 25 is firmly secured two plates on which are formed escapement fingers 28 and 29 and with these plates are associated cam members 30 and 30a. The spring 27 serves to hold the parts as indicated in Figure 16 with one of the pegs P in a position wherein it is slid down the channel or track apart the finger 28, but in engagement with the finger 29. The fingers 28 and 29 are spaced apart the diameter of one peg, so as to take one peg between them. The position of a peg against the finger 29, however, is but momentary, for, under normal conditions, the plate 23 is retracted into the position shown in Figure 4, so that said plate engages with the cam member 38 and thus tilts the escapement fingers, so as to retract the finger 29 and force the finger 28 into the path of the gravitating pegs. Thus under normal conditions, the pegs are held together by the finger 28, while one peg of each track has passed beyond the finger 29 and is resting on a substantially horizontal part of the track as indicated in dotted lines in Figure 4. In other words, there is at all times a peg in substantially the dotted line position of Figure 4 for each track awaiting the pleasure of the operator. Now if any appropriate key 20 is operated, the swinging plate 23 will move in a clockwise direction away from the escapement mechanism and will disengage from the cam member 30a so that the spring 27 will force the parts into the position of Figure 16 and the foremost peg will gravitate into engagement with the finger 29.

As the plate 23 continues to swing in a clockwise direction, the nose 24 will engage with the back of the peg previously fed and force it along the horizontal portion of the track until it engages with the stop bar 31 and the stop plate 32. These parts illustrated in Fig. 17 have notched forward edges so that as the nose 24 forces the peg forwardly, said peg will come to rest in a position shown in Fig. 17 with the respective portions of the peg bearing against the semicircular notches indicated in this figure. This will hold the peg upright but as the peg leaves the end of the track it will drop slightly until the flange 33 of the peg engages with the up-

per faces of the stop bar 31. By this time, however, the lower end of the peg will have dropped far enough to partially enter the seat 34 in the top of the corresponding wrench.

70

In accordance with this invention, as in my prior case, the number of pegs desired to be applied to any one row of the particular bar are fed one after the other into cooperation with the respective wrenches and all the pegs are fed before any wrench is operated. After this particular set up of pegs is, however, in position with respect to the wrenches, all of the wrenches are forced upwardly to screw all of the pegs simultaneously into the bar positioned in cooperative relation to said wrenches.

75

The means for operating the wrenches embodies a wrench bar 35 which extends transversely of the machine so as to underlie the wrenches. In practice, the wrenches are all secured to this bar in a detachable manner so as to permit of displacement that when the bar is raised and lowered, all the wrenches are simultaneously operated so as to apply all the pegs which may have been previously fed thereto.

80

Extending transversely across the machine is a shaft 36 and on this shaft are mounted a plurality of cams to actuate the bar 35. One of these cams is indicated at 37 and is positioned midway of the length of the shaft. A similar cam may be positioned on each side of the center cam 37 while a closed cam, such as indicated in Figure 3, is associated with each end of the shaft 36. The purpose of these cams is to apply force at different points in the length of the bar so as to more uniformly apply the force to all of the wrenches at once. The purpose of the closed cams of Fig. 3 is to insure the retraction of the parts after the pegging operation and at the same time to make necessary the completion of the pegging operation before retraction. The closed track cam of Figure 3 is designated generally by the reference character 38 and it has therein a closed track 39 and is also provided with a curved ratchet face 40. All the cams are of course fixed to the shaft 36. The ends of the bar 35 are reduced to form a circular trunnion 41 which operates in the closed tracks 39 as shown.

90

Affixed to the opposite ends of the shaft 36 is a U-shaped bail or operating handle 42 which constitutes one form of a suitable prime mover. It is shown in its retracted position, in Fig. 1 for example, but it is adapted to be moved to bring about operation of the cams in a counter-clockwise direction and into a substantially horizontal position, to oscillate the shaft 36 through an angle of approximately 90 degrees. When in the position of Figure 1, all of the cams are on their low phases. If, however, the handle is drawn forwardly through approximately 90

95

100

105

110

115

120

125

130

degrees, the cams will act upon the wrench bar to force all of the pegs into position with respect to the superimposed bar C, in the same manner as in my prior machine.

It will be noted, however, that as the wrench bar moves upwardly to apply the pegs, it engages with a nose 43 on a link 44. Two of these links are mounted on coaxial fixed pivots 45 and are pivotally secured at their upper ends as at 46 to the stop bar 31 which also carries the stop plate 32, so that when the wrench bar has moved upwardly sufficient to cause the pegs to extend well into the seats of the wrenches, the stop bar 31 and stop plate 32 will be thrown back out of the way so that the wrenches can continue to elevate and force the pegs into position in the appropriate chain bar C.

After the several swinging plates 23 have been operated, they remain in their forward or operated positions until the wrench bar is elevated to apply the pegs at which time a flange 35a carried by said bar engages with cam surfaces 23a on all of said swinging plates as indicated in Figure 4 and returns all the plates simultaneously into their retracted positions.

As they swing back into such retracted positions, they pass by the cam members 30 because the springs 27 are holding said cam members out of the path of the swinging plates, but as the swinging plates approach and reach their fully retracted positions indicated in Fig. 4, they engage with the cam members 38 and tilt the escapement to permit one peg of each track to go forward into the dotted line position shown.

As the wrench bar thereafter descends, the parts 31 and 32 reassume their original position to receive the next series of pegs and to stop them in correct positions with respect to the wrenches.

The purpose of the ratchet 40 is to assure completion of the peg applying stroke. As shown in Figs. 1 and 3, a pawl 47 is pivoted on a boss 48 carried by the side plate 2 and which pawl is adapted for cooperation with the ratchet 40. The pawl is provided with two notches 49 and 50 with which cooperates a spring pressed plunger 51. When the handle 42 is drawn forwardly, the pawl will ride idly over the ratchet 40 until the end of the stroke when a lug 52 will engage the pawl and pivot it so as to engage the notch 49 with the plunger 51. This will retract the pawl from the ratchet so that the handle may be returned to its initial position. As it substantially reaches its initial position, a pivoted stop 53 will engage with a pin 54 on the pawl 47 and cause the pawl to be swung to engage the notch 50 with the plunger 51 so that on the next forward operating movement of the handle, the pawl will be in cooperative relation with the ratchet. By this arrangement, it will appear that an operat-

ing movement of the handle has been started, this movement will not be reversed until completed and this insures a complete application of the pegs at each operation and obviates the possibility of incomplete pegging 70 of the chain.

In order to facilitate the operation of the keys for the selective feed of the pegs, I preferably associate with the machine an automatic device for disclosing to the operator the keys which should be operated for each particular set up in order to produce the predetermined weave design.

This mechanism is shown best in Figs. 1, 11, 12 and 13. It embodies a roll 55 with which is associated a guide 56 so that a strip of paper constituting a chart 57 may be fed about the roll 55 with a step by step movement. On this strip of paper or chart are transverse lines or rows of characters and the roll is covered by a suitable housing 58 having therein a slot 59 through which one row of characters may be seen at a time. To one end of the roll 55 is secured a ratchet wheel 60 with which cooperates a pawl 61 which extends rearwardly through the machine and is secured to an actuating member 62. This member is in the form of a bell crank pivoted at 63 to a fixed pivot. The bell crank is shaped to straddle the wrench bar 35 (see Fig. 13) and has a finger 64 which extends into a depression in the rear end of the part 61. Every time the wrench bar 35 is elevated, it draws the pawl 61 back and every time that the bar 35 is lowered, it forces the pawl 61 forward, so that by this operation, the pawl acts upon the ratchet to advance the latter as required for either single or double harness chains, depending on whether a relatively deep or shallow pawl nose is connected at the joint 70.

Thus in practice the operator looks through the slot 59 and by reference to the line of the chart which is visible therethrough ascertains what keys are to be operated. After operation of such keys, the handle 42 is actuated to insert the pegs which have been fed by the operation of the keys and simultaneously with the operation of the handle, the chart is advanced to the next line which corresponds to the next chain bar. Proper feed of the chart is insured by means of a pressure roll 65 which has a relatively narrow pressure band 66. The roll 65 rotates on the pin 67 carried by a bracket pivoted at 68 and spring pressed at 69 to cause the part 66 to hold the chart in frictional driving relation with the roll 55.

The pawl is preferably jointed as indicated at 70 to permit it to be swung back free from the ratchet 60 while introducing the chart and adjusting the same to proper position with reference to the slot 59.

I have hereinbefore stated that a chain of bars is fed to the roll 5 and thereafter to 130

the peg removing mechanism 16 before being fed to the roll 4. This peg removing mechanism is best shown in Figs. 5, 6, 7 and 18.

Formed in the upper portion of each of the side plates 2 and 3 are two sets of guideways designated 71 and 72. At the forward ends of the guide ways 71 is a fixed holder 73, the structure of which is illustrated in Fig. 18. The holder is provided at its forward face with a transverse channel extending for substantially the entire width of the machine between the side plates 2 and 3, and this channel designated 74 is shaped to form a seat into which the bars are received in succession. The channel is shaped so that the bars will seat snugly therein with the peg holes of the bars in alignment with correspondingly positioned holes 75 extending through the bar from the base of the channel. With these holes are adapted to cooperate plungers 76 mounted in a cross head operable in the guide ways 71. The cross head embodies a U-shaped channel section 77 within which is received an operating bar 78 and directly adjacent thereto a plunger bar 79. The plunger bar and operating bar are held in place in the channel section by a suitable locking plate or other convenient means 80. The plungers 76 are mounted on the plunger bar 77 and extend through holes in the operating bar 78 and thence extend into and are guided by the holes in the stationary guide 73, so that when the cross head is operated by means presently to be described, so as to traverse the guideways 71, the plungers 76 will move from the position of Fig. 5 to the position of Fig. 6 and vice versa. The purpose of the plungers is to force the pegs from a bar positioned in the channel or seat 74 and in the operation of the machine this is accomplished by the bar 81 which reciprocates after the manner of a cross head in the guideways 72. The bar 81 is shown in detail in Fig. 7. It is illustrated as having therein a slot 82 through which the pegs may be discharged from the chain bars. In practice, the parts are so operated that the bar 81 moves from its normal retracted position of Fig. 4 in a rearward direction to force a juxtaposed chain bar into the seat 74 shown in Fig. 18 and the plunger cross head then moves forwardly to drive the plungers 76 through the holes 75 and force the pegs from the chain bar so that they are discharged through the slot 82 and are guided by suitable apron (not shown) directly back of the hopper 17. The plunger bar 79 is so arranged as to be readily removable from the plunger cross head to permit of substitution of bars as occasion may require.

For example, when operating with a double harness chain a plunger bar having two rows of plungers would be inserted in the cross head, whereas when a single harness chain is used, a plunger bar with a single row

of plungers should be used. In practice, the arrangement is such that these bars may be readily substituted as occasion may require and when in position will serve to force out all of the pegs from the bar C while the latter is held tightly to the seat 74. After the pegs have been removed from any particular bar C, the cleared bar moves on one step and another bar C with the pegs therein comes into position for removal whereupon the operations described are repeated.

The mechanism for moving the part 81 and the plunger cross head is as follows. The part 81 is provided at its opposite ends with trunnions 83 which extend beyond the outer faces of the plates 2 and 3 and engage with cam slots 84 in cam plates 85 pivoted to oscillate about trunnions 86, which are carried by the end of the bar 73, as shown in Fig. 18.

The plunger bar is similarly provided at its opposite end with trunnions 87 which extend into cam slots 88 in the cam plates 85. The cam plates are connected by means of links 89 to operating arms 90 rigid with the shaft 36 as shown in Figure 1. Thus when the handle 42 is pulled down on its operating stroke to force the wrenches upward and apply a row of pegs to a chain bar supported by the lower cylinder, the links 89 will bring about rotation of the cam plates 85 from the normal position shown in Fig. 1 to the opposite terminal positions shown in Fig. 2. The cam slots 84 and 88 are so shaped that during this operation the two upper cross heads will be brought together to bring about the ejection of the pegs as described.

As the handle 42 is returned to its normal position, the links 89 will bring about a reversal of rotation of the cam plates 85 and as this operation proceeds the following operations take place.

A pin 91 on one of the cam plates 85 will engage with the lower end of a feed lever 92 which is pivoted on the end of one of the trunnions of the upper cylinder. The upper end of this feed lever has a laterally extending finger 93 which engages with a ratchet wheel 94 substantially the same as the ratchet wheel 12 and fixed to the end of the upper roll so that continued movement of the pin 91 will swing the operating lever 92 and advance the upper roll one step. Simultaneously with this operation, a pawl 95 pivoted at 96 to the plate 85 is lowered from the position of Fig. 2 until the nose 97 of the pawl engages the nose 98 of a gravity latch 99. As the pawl descends it operates the gravity latch 99 into the dotted line position shown in Fig. 1 and permits the nose 97 of the pawl to enter between the teeth of the ratchet wheel 12.

Upon continued movement of the plate 85, the pin 100 comes to the end of the slot 101, so that as the plate continues to rotate the

pawl imparts rotary movement to the ratchet 12 to advance this ratchet one step, but it will be noted that the nose 97 holds the gravity latch free from engagement with the ratchet 12 long enough to permit movement of the pawl before gravity again causes the latch to move into a position to engage with the next tooth and positively control the extent of the operating movement of the lower roll.

During the next operation of the handle, the upward movement of the links 89 causes one of them to engage with the lower weighted end of the pawl lever 92 and swings said pawl lever in a clockwise direction. The pivotal connection of the lever 93 is provided by an elongated slot 102 and this allows the lever to rise during its retrograde movement sufficiently to rise over one tooth of the ratchet 94 until it comes to the next space 20 where gravity again causes the extension 93 to engage with the next tooth and upon subsequent clockwise movement of the plate 95, the operations described are repeated.

In the manner described, a chain of bars 25 is passed over the upper roll, thence to the peg removing mechanism, thence to the pegging mechanism and thence out of the machine. During the passage of the bar chain, it is advanced step by step through the various operations which I have described, and the operating lever 9 serves to adjust the lower roll 4 as may be desired to insure proper alignment between the holes of the bar and the peg wrenches, so as to provide for the pegging of bars C appropriately to either single or double harness. Provision is made for the use of chain bars of different standard lengths for as shown in Fig. 10, I provide filler pieces 103, each of which is provided at its back with a headed projection 104. The filler pieces 103 have tapered sides to correspond to the taper of the channels 15 and the ends of the bars C and the headed projection 104 are adapted to cooperate with any one of a series of keyhole slots 105 formed in the base of each of the channels 14 and 15 to control the effective length of the corresponding channel. These filler pieces may be easily slipped into position or removed and thus provide for the movement of the machine to act upon bars C of different standard lengths.

It will be apparent from the foregoing detailed description of the preferred form of the invention which I have disclosed that the machine embodies numerous features important in the art to which it pertains. It provides simple and effective mechanism whereby loom chains after use can be fed to the machine, the old pegs removed and new pegs inserted in any predetermined combinations dependent upon the will of the operator and during these operations, the operator may have before him an automatically operable chart to guide him in his operation of the machine. The mechanism eliminates

a very appreciable amount of tiresome labor and accomplishes the results for which it is intended in a thoroughly trustworthy and efficient manner. Moreover, the pegging is uniform, each peg being inserted to exactly the same extent as every other peg, thus imparting to the chain a uniformity which it is impossible to obtain in a manually pegged chain.

The drawings illustrate the invention in its preferred, practical form, but the invention is to be understood as fully commensurate with the appended claims.

Having thus fully described the invention, what I claim as new and desire to secure by Letters Patent is:

1. In a machine of the character described, the combination of means for feeding a bar chain with step by step movement apast peg removing and peg applying stations in succession, means operable at the peg removing station to remove any and all pegs from the bars fed thereto, and means operable at the peg applying station to apply pegs in various combinations to the thus cleared bars.

2. In a machine of the character described, means for removing pegs from a pegged loom bar, means for applying pegs in various combinations to a bar from which pegs have been previously removed, means for positioning pegs in positions to be applied to a bar, a prime mover, and operative connections between the prime mover and the peg removing and peg applying means to operate the peg removing and applying means in predetermined sequence.

3. In a machine of the character described, means for removing pegs from a pegged loom bar, means for applying pegs in various combinations to a bar from which pegs have been previously removed, means for positioning pegs in positions to be applied to a bar, a prime mover, and operative connections between the prime mover and the peg removing and applying means for operating both the peg removing and applying means from said prime mover.

4. In a machine of the character described, means for removing pegs from a pegged loom bar, means for applying pegs to a bar from which pegs have been previously removed, means for positioning pegs in positions to be applied to a bar, a prime mover, and operative connections between the prime mover and the peg removing and applying means for operating both the peg removing and applying means from said prime mover, said operative connections including means for successively feeding bars to the peg removing means and from thence to the peg applying means.

5. In a machine of the character described, means for guiding and feeding a loom bar chain along a predetermined path with step by step movement, means positioned adjacent

- the path of movement of the chain to hold the bars thereof successively in stationary position during periods of dwell of the chain, mechanism including a plurality of plungers to force pegs from a bar, while thus held in place, means positioned further along the path of movement of the chain to successively hold the thus stripped bars in position during periods of dwell in the movement of the chain, and means for applying a new combination of pegs to the bars individually while holding in the latter position. 10
6. In a machine of the character described, means for guiding and feeding a loom bar chain along a predetermined path with step by step movement, means positioned adjacent the path of movement of the chain to hold the bars thereof successively in stationary position during periods of dwell of the chain, mechanism including a plurality of plungers to force pegs from a bar, while thus held in place, means positioned further along the path of movement of the chain to successively hold the thus stripped bars in position during periods of dwell in the movement of the chain, and means for applying a new combination of pegs to the bars individually while holding in the latter position, and a common prime mover for simultaneously applying power to both the peg removing and the peg applying means. 20
7. In a machine of the character described, means for guiding and feeding a loom bar chain along a predetermined path with step by step movement, means positioned adjacent the path of movement of the chain to hold the bars thereof successively in stationary position during periods of dwell of the chain, mechanism including a plurality of plungers to force pegs from a bar, while thus held in place, means positioned further along the path of movement of the chain to successively hold the thus stripped bars in position during periods of dwell in the movement of the chain, means for applying a new combination of pegs to the bars individually while held in the latter position, a common prime mover for simultaneously applying power to both the peg removing and the peg applying means, means for selectively positioning pegs in different predetermined combinations in positions to be applied by the peg applying means, and means operable by the prime mover to actuate a chart to show the operator the particular pegs which it is necessary to position for each bar to produce a predetermined weave design. 30
8. In a machine of the character described, means for feeding a bar chain along predetermined path with intermittent periods of rest in the feed of the chain, means cooperating with the chain at one point in its path of travel to remove from the bars thereof pegs which may be associated therewith, means positioned further along the path of travel of the chain for applying pegs to the bars, key operated mechanism for feeding pegs in predetermined combinations into positions to be applied to the bars by peg applying means, and means operable in timed relation to the peg applying means to show to the operator what keys should be operated to peg each particular bar in accordance with a predetermined weave design. 40
9. In a machine of the character described, means for holding a loom bar in position to receive a plurality of pegs, means for simultaneously applying a plurality of pegs to the bar, means for selectively feeding variable numbers of pegs in variable arrangements to the peg applying means, a chart and chart feeding means to move the chart in timed relation to the operations of the peg applying means to show the operator what pegs should be applied to each particular bar. 50
10. In a machine of the character described, means for holding a loom bar in position to be operated upon, means for selectively positioning a plurality of pegs in a position to be applied to the bar, means for simultaneously applying to the bar a plurality of pegs so positioned, and means to show the operator the particular pegs to be fed to each bar to produce a predetermined weave design. 60
11. In a machine of the character described, means for holding a loom bar firmly in position, a plurality of plungers guided for simultaneous movement into and out of the individual peg holes of the bar from the back of said bar, and means for forcing said plungers through the holes of the bar while the bar is thus held in position for the purpose of forcing any pegs which may be associated with the holes in said bar. 70
12. In a machine of the character described, a plurality of plungers mounted for simultaneous rectilinear movement, means for positioning a loom bar with the individual holes in the bar axially aligned with respect to the corresponding plungers and for holding the bar firmly in this position, and means for thereupon forcing the plungers through the peg holes of the bar for the purpose of removing from the bar any pegs which may be associated therewith. 80
13. In a machine of the character described, a bar supporting member provided therein with a channel in which a loom bar is adapted to seat, and a filler block detachably positioned in the channel and adjustable with reference to the length of said channel to vary the effective length of the channel and adapt the same to loom bars of different lengths. 90
14. In a machine of the character described, a member adapted to support a loom bar and provided therein with a channel in which the bar is adapted to seat, there being a key slot in the base of the channel, and a filler block adapted to seat in the channel 100

and provided on its back with a headed stud to engage with the key slot for the purpose of retaining the filler block in the channel.

15. In a machine of the character described, a wrench for forcing a peg into a loom bar, means for feeding a peg into alined axial relation with the wrench, and means to arrest the movement of the peg when it reaches such alined relation and to hold the peg in such alined relation until engaged by the wrench.

16. In a machine of the character described, a track along which pegs are adapted to be fed to a point of application, escapement mechanism cooperating with the track and adapted when operated to allow of passage of the pegs one at a time, and manually operable means for operating the escapement mechanism to release one peg and to thereupon positively move said peg to the point of application.

17. In a machine of the character described, means for feeding a bar chain along a predetermined path, a hopper, means positioned along the path of feed of the chain to remove from the respective bars any pegs that may be associated therewith, means for feeding the thus removed pegs into the hopper, means for selectively feeding pegs from the hopper into a position to be applied to the thus cleared bars, and means for applying to the bars the pegs thus fed.

18. Guide chart operating mechanism for loom bar chain pegging machines embodying a chart having characters thereon, a casing provided therein with a side opening through which a single row of characters on a chart may be observed, and means for positioning successive rows of characters on the chart in juxtaposition with said opening to show an operator what pegs should be applied to the respective bars to produce a predetermined weave design.

19. In an apparatus for removing pegs from a bar chain, a bar support provided therein with a seat shaped to receive and fit a bar, means for intermittently moving a bar chain past said support, means to position the bars successively in said seat during consecutive periods of dwell of the chain and to momentarily hold said bars to said seat, a plurality of plungers operable through said seat and respectively alined with the peg holes in the bar held in said seat, and means for reciprocating the plungers through the peg holes of each bar as it is held to said seat for the purpose of removing from said bar such pegs as may be contained in said holes.

In testimony whereof I have signed the foregoing specification.

FRED UTTLEY.
